(57) **CLAIM**

The ornamental design for an air conditioner, as shown and described.

DESCRIPTION

FIG. 1 is a perspective view of an air conditioner of the present disclosure;

FIG. 2 is a front elevational view of the air conditioner shown in FIG. 1;

FIG. 3 is a rear elevational view of the air conditioner shown in FIG. 1;

FIG. 4 is a left-side elevational view of the air conditioner shown in FIG. 1;

FIG. 5 is a right-side elevational view of the air conditioner shown in FIG. 1;

FIG. 6 is a top plan view of the air conditioner shown in FIG. 1;

FIG. 7 is a bottom plan view of the air conditioner shown in FIG. 1;

FIG. 8 is an enlarged fragmentary view showing a portion of FIG. 1; and,

FIG. 9 is an enlarged fragmentary view showing another portion of FIG. 1.

The broken lines shown in the drawings illustrate portions of the air conditioner that form no part of the claimed design. The broken lines shown encircling portions of the air conditioner in FIG. 1 illustrate enlarged views in FIGS. 9 and 10 and form no part of the claimed design.

1 Claim, 9 Drawing Sheets
